MISSILE LAUNCHER

Robert E. Carlberg and Frank W. Sieve, Falls Church, and Rocco De Masi, Arlington, Va.

Original application September 1, 1950, Serial No. 182,696, now Patent No. 2,745,317, dated May 15, 1956. Divided and this application February 16, 1954, Serial No. 410,470

11 Claims. (Cl. 89—1.7)

(Granted under Title 35, U. S. Code (1952), sec. 266)

The invention described herein may be manufactured and used by or for the Government of the United States of America for governmental purposes without the payment of any royalties thereon or therefor.

This application is a division of application Serial No. 182,696, filed September 1, 1950, now U. S. Patent No. 2,745,317, for Missile Launcher, which is directed to a combination of several inventions by joint inventors Arthur J. Stanton, Robert E. Carlberg, Robert K. Bole, Frank W. Sieve, William Danziger, and Rocco De Masi.

This invention relates to missile launchers and more particularly to missile launchers which are automatic in operation and may be controlled from a remote firing station.

In the art of modern warfare the use of self-powered missiles such as rockets has been receiving increasing attention, however, difficulties have been encountered in the handling and launching of such missiles particularly when it is desired to launch a number of them in rapid succession.

Heretofore, devices for launching a multiplicity of rockets have been in the form of relatively simple construction comprising a rack or frame for supporting a number of rockets side by side and means for firing all of the rockets substantially simultaneously whereupon they are broadcast in the general direction of the target. When adapted for shipboard use such devices ordinarily could not independently be moved in train or elevation and their firing accuracy depended upon directing the ship toward the target and arriving at a prescribed range before the missiles were released. It will be apparent that to obtain repeated firing with such an arrangement it was necessary for the launcher to be loaded by hand from above-deck with exposed personnel and this loading step had to be repeated before the launcher could again be fired.

The risks attendant to the exposure of large numbers of rockets and personnel above-decks is readily apparent.

In order to avoid hazard to shipboard personnel loading rockets in an exposed position, there have been developed gravity fed or mechanically fed rocket launchers which fire rockets one by one through a firing trough. However, in such arrangements ordinarily the supply of rockets still must occupy an exposed position and hence is vulnerable to a hit by the enemy.

A further problem, particularly with large rockets, arises out of the tremendous heat generated by the rocket blast as it is fired. Because of the tremendous heat and blast effects of the rocket as it is launched, it is important that the launcher be automatically loaded and capable of being operated in train and in elevation by remote control means such as the conventional gun director employed aboard ship.

The missile launcher of the present invention overcomes the above and other limitations of prior art devices and is particularly adapted for use on naval vessels where space limitations are important, however, it will

2

be understood that it is not limited to such use but may be used in other installations where a launcher of this character is desired.

Accordingly, it is an object of the present invention to provide an improved missile launcher design which provides optimum control of the missile during launching, is rapid in action and avoids the hazards incident to the use of conventional missile launchers.

A further object of the present invention is to provide a missile launcher that may be completely automatic in operation and may be controlled from a remote station by suitable control equipment.

Still another object of the present invention is to provide a launching guide tube having a loading position and a launching position and means for moving the guide tube between the loading and the launching position.

Another object of the present invention is the provision of improved loading means whereby missiles may be supported in a magazine disposed beneath the launcher mount and under the deck structure and carrying a supply of missiles such as rockets which are individually positioned adjacent a vertical hoist for movement into the missile launcher guide.

A further object is the provision of an improved missile launcher installation wherein the structural relationship between the above-deck mount and below-deck magazine and hoist may be varied to conform with structural and space limitations of various naval vessels upon which it may be installed.

Another object is the provision of means for safely conveying an unfired missile from the launcher guide back to the missile magazine.

A further object is to provide apparatus to facilitate the lowering of missiles from above-deck into a ship's stowage magazine.

A still further object is to provide means for loading missiles from the ship's stowage magazine into a launcher ready service magazine.

Other objects and many of the attendant advantages of this invention will be readily appreciated as the same becomes better understood by reference to the following detailed description when considered in connection with the accompanying drawings wherein:

Fig. 1 is a vertical side elevation with portions removed showing one embodiment of the present invention in stowed condition;

Fig. 2 is a similar view from the opposite side but with the parts arranged in loading position;

Fig. 3 is a side elevation with the launching tube disposed in firing position;

Figs. 4 to 9, inclusive, are schematic views illustrating the positions of the launching tube, launcher hoist, and ready service magazine during loading and firing operations;

Fig. 29 is a time chart showing the relative movement of the launcher hoist, the launcher guide and ready service magazine during one complete cycle of automatic operation; and

Fig. 30 is a schematic view showing the method of lowering missiles from above-deck to the ready service magazine and thence by the stowage hoist to the missile stowage magazine or locker.

The present invention is shown as a shipboard type of missile launcher installation wherein all components except the launcher guide tube are protected by enclosure within a shield or by location below-deck. The launcher may be remotely controlled and automatically operated by connection to a suitable control system forming no part of the present invention.

In the embodiment illustrated, a single launcher guide tube is supported by trunnions for pivotal movement from an upright loading position to an inclined firing position at which time it is lowered to some angle between 0° and 60° of elevation as determined by a signal received from the ship's gun director. This guide tube and its trunnions are mounted upon a carriage supported upon a mount which is similar to the conventional 40 mm. gun mount and includes the necessary apparatus for moving the guide tube both in train and elevation in response to director signals received from conventional fire control equipment. By this means the mount may be moved in train and in elevation so that it may bear upon the target up to the very instant of firing.

A second component of this launcher is a hoist mechanism which operates to deliver rockets or other missiles from a below-deck ready service magazine into the

launcher guide tube when it is at its 90° elevated or loading position.

A third component is a below-deck ready service magazine in the form of a large upright drum having a plurality of missile receiving stalls spaced about its periphery. By suitable means the drum may be rotated to successively present missiles to the launcher hoist for loading into the guide tube.

A fourth component of the present invention is the provision of a stowage hoist whereby missiles may be supplied to the stalls of the ready service magazine from a remote missile stowage compartment so as to replenish the supply of missiles in said ready service magazine during a period when the launcher is not in automatic operation. This stowage hoist embodies transfer means including a tray upon which the missiles may be loaded and which tray then tilts to transfer the missiles from a horizontal stowed position to an upright position in alignment with the stowage hoist whereupon they may be moved into empty stalls of the ready service magazine.

The first three components above set forth work together during automatic firing operation to automatically and continually load and fire missiles until the supply in the ready service magazine has been exhausted or until a "cease fire" order is given. Thereafter the last component works to reload the ready service magazine so that it will be ready for another burst of automatic fire. These operations may be carried on in timed relationship under the control of suitable electrical and hydraulic interlocks, the details of which form no part of this invention but which may be employed, if so desired, to assure the completion of each step before the start of the next.

In normal service, operation of the missile launcher may be remotely controlled by a director fire control system. When the launcher is in operating condition, and is following the director, the entire magazine supply of 22 missiles may be loaded and launched in succession simply by closing the firing circuit and holding it closed. During this automatic loading and launching operation, no action is required of launcher personnel. The firing of the launcher may be controlled remotely, as aforementioned, and successive loading of missiles from the ready service magazine may be performed automatically by the missile hoist. Hence, under these conditions personnel are not stationed in or about the mount above-deck during firing operation.

Local control features of train and elevation are not incorporated in the launcher, however, handwheels are provided to move the mount manually in train and elevation for the performance of stowing and casualty operations and to facilitate service or maintenance work. Local control of the firing circuit may be provided at a below-deck control station as an alternative to director firing.

In the embodiment of the invention illustrated, and referring particularly to Figs. 1 to 12, inclusive, the present missile launcher is shown as it may be installed on a naval vessel with an above-deck mount generally designated 100, a below-deck ready service magazine 101 and a missile hoisting mechanism 102 adapted to convey missiles from the magazine directly into a missile guide tube 103 carried by the mount.

The above-deck mount 100 is provided with a suitable protective shield 104 resting upon a shield base 105. Within the shield is mounted a carriage 106 having spaced cheeks 107 and 108 mounting trunnion bearings 109. The guide tube 103 has trunnions 110 supported in the bearings 109 about which the tube may pivot from an upright loading position to an inclined firing position, the tube 103 being provided with a gear sector 111 which may be engaged by the usual drive pinion to move the tube in elevation.

In the embodiment illustrated the device is shown supported upon deck 114 by means of a flanged roller bear-

ing stand 115 and in use the entire above-deck launcher mount may be rotated in train while the launcher tube is simultaneously moving in elevation.

Immediately below the deck 114 may be located the launcher magazine or ready service magazine 101 which in the present embodiment includes an upright drum mounted upon a suitable bearing 116 for rotation about its vertical axis 117. As shown in the top view Fig. 10, a number of missiles 118 may be supported in stalls 119 formed by guide rails 120 spaced about the periphery of the ready service magazine and so arranged as to bring each missile into axial alignment with the center of rotation of the mount as the magazine is indexed during a missile loading operation.

When a missile has been moved into alignment with the axis of rotation of the launcher mount and the guide tube 103 is vertical, the missile may be automatically raised from the ready service magazine into the guide tube by means of a launcher hoist 102, the sequence of operation of which is schematically illustrated in Figs. 4 to 9, inclusive. In Fig. 4 the guide tube 103 supported upon the carriage 106 is shown in the vertical loading position and the ready service magazine 101 is shown loaded with several missiles 118, one of which 118a, is located in coaxial alignment immediately below the upright guide tube 103. The rear or shroud 121 of the missile is positioned at that time just above a hoist lifter member 122.

In Fig. 5 operating switch 123 has been closed and, as the first step of the automatic launcher operation, the hoist 102 is energized, by any suitable means, to raise lifter 122 by means of a rammer type one-way chain 124 so as to lift the missile 118a into the guide tube 103 where it is retained by suitable retaining latches hereinafter described. As shown in Fig. 6, the rammer then descends and guide tube 103 pivots about its trunnions to the firing elevation as determined by the conventional fire director means aboard ship and, as shown in Fig. 7, as soon as the hoist lifter reaches the bottom the ready service magazine may index to move another missile 118 into the loading position.

When the guide tube 103 descends to the desired elevation the missile may be automatically fired as indicated in Fig. 8, whereupon the guide tube 103 starts automatically to return to its upright position as shown in Fig. 9. If switch 123 is maintained closed, then the hoist 102 automatically proceeds to load another missile into the guide tube from the ready service magazine 101. This operation continues until switch 123 is opened or until the supply of missiles in the ready service magazine is exhausted.

The above-deck mount

The above-deck mount 100 receives missiles from below through a central opening 125 (Fig. 17) in a rotatable base ring 126 supported on roller bearings 127, 128 and 129. As is shown in Fig. 2, the guide tube 103 in its vertical loading position is disposed with its longitudinal axis in coaxial alignment with the axis of rotation of the above-deck mount and hence missiles fed from below by hoist 102 are received directly into the after end of the guide tube 103.

The guide tube 103 (Figs. 13 and 14) comprises a cylindrical tube member 130 preferably formed of sheet steel and having spaced about its inner surface a plurality of inwardly projecting guide rails 131. Tube 130 may be removably secured in a guide tube engaging sleeve 132 extending from a guide tube housing 133 from the sides of which the trunnions 110 extend. Because of the substantial absence of recoil the trunnions need not be large. A spanner nut 134 may secure the guide tube 130 in the guide tube receiving sleeve 132.

An elevating gear sector 111 is secured to the undersurface of the guide tube housing 133 and may be engaged by the usual operating pinion of conventional elevating mechanism so as to elevate the guide tube in response to

fire control signals. In order to retain a missile in the guide tube after the launching hoist rammer is lowered, there may extend into the after end of the tube a pair of oppositely disposed, hinged, spring biased missile support latches (Figs. 14 and 15) which latches are mechanically cammed out by a missile entering the vertically positioned guide tube and snap into place behind the lower edge of the missile shroud when the hoist has raised the missile clear. Subsequent lowering of the hoist lifter member leaves the missile supported in the guide by these latches. A forward missile restraining latch 137 normally protrudes into the bore of the guide forward of the missile shroud 121. This latch is held retracted by a solenoid when the guide is empty or when it is locked in loading position but after the guide is loaded this latch prevents the missile from sliding forward as the guide depresses to the firing position.

When all other actions necessary to firing have been completed the missile restraining latch 137 is withdrawn by its operating solenoid and the firing circuit may thereafter be completed. As is shown in Fig. 14, the rear of the guide tube 130 is enclosed in a breech sleeve 138, the after end of which is notched to receive the missile engaging latches 135. The latter are hinged so that toe portions 139 normally project into the bore of the guide tube but entry of a missile from below cams the latches outwardly against the tension of a latch spring 140, the fixed end of which is secured to a latch spring bracket 141 welded or otherwise suitably secured to the breech sleeve 138. The other end of the spring 140 is secured to the upstanding arm of an L-shaped bracket 136 bolted or otherwise secured to the external surface of the missile engaging latch 135 whereby the tension of spring 140 serves constantly to urge the toe 139 into the guide tube. The missile engaging latches 135 are linked together so that they may be moved in unison by latch operating lever 142 keyed to shaft 143. An arm 141a is also keyed to shaft 143 so that movement of the handle 142 raises arm 141a against the undersurface of bracket 136 to lift it and withdraw the toe 139. By link lever 146 secured to arm 147, as shown, the lower missile engaging latch 135 may simultaneously be retracted.

Normally the missile engaging latches 135 will not manually be retracted from the guide tube, however, during testing operations etc. it may be necessary to remove a missile from the after end of the guide tube and then handle 142 may be raised about its pivot 143 to cam up bracket 136 and withdraw the toes 139 of the missile engaging latches 135. A detent including knurled thumb nut 146a may be operated to screw the threaded end of a bolt 147a into a threaded opening in boss 148. Loosening of this detent is necessary before handle 142 may be operated. To retain the handle 142 in the missile engaging latch retracted position, a finger latch 196 controlling a spring biased bolt 197 is mounted in a bolt block 198 and when the handle 142 is raised the bolt 197 moves into the path of projection 199 on the lever 142 and holds it in missile supporting latch retracted position until the finger latch 196 is operated.

In order to indicate the condition of the missile engaging latch there is provided a switch AE whose roller tipped actuating arm is positioned in the path of a tripping lug 149 of the bracket 136 to indicate when the upper missile engaging latch has been completely retracted. A similar switch AC is located with its roller tip actuated arm disposed in the path of a cam member 151 mounted upon the bracket 136 and serving to indicate when the upper missile engaging latch is in normal position. The underside of the guide tube is provided with similar switches AB and AD which are operated by the positioning of the lower missile supporting latch. This is because of possible interference by the hoist lifter member with one of the latches.

Toe 139 of each missile engaging latch is preferably inclined on its forward face to prevent manual release

of the latch unless the weight of the missile has first been removed by the hoist lifter member.

The forward missile restraining latch 137 disposed ahead of the missile shroud when the missile is located in the launcher tube is illustrated in detail in Fig. 15 and may be supported for pivotal movement around a pin 150. It has a bell crank arm 152 which may be linked to a plunger rod 153 for actuation by a solenoid SAF housed within the container 154. If desired the forward missile restraining latch 137 may be actuated by mechanical means instead of the solenoid SAF aforementioned and, to accomplish this, the upper arm of the bell crank 152 is provided with a pad 155 which is located to be engaged by the rounded end of a manually actuated arm 156 (Fig. 16) supported upon a transversely extending operating shaft 157 extending to the outside of a suitable blast chamber for operation by a hand crank 158 for the purpose of permitting manual removal of a missile from the front end of the guide tube in a manner hereinafter to be described.

As shown in Figs. 14 and 15 there may be provided a firing pin including an upwardly extending terminal 280 and an inwardly directed shroud engaging pointed tip 281 which latter is resiliently urged against an electric contact band 282 about the periphery of the missile shroud. The tip is preferably of extremely hard material such as "Stellite" so as to engrave the band 282 and insure positive electrical contact therewith.

As shown in Fig. 13 the guide tube is provided with a bore clear indicator in the form of a long shoe 159 located within the tube and the presence of a missile in the guide tube depresses the shoe 159 and rotates a support shaft located within the tubular housing 160 which in turn may, if so desired, actuate switch means within the switch box 161 and may be connected to a control circuit to show that the guide tube is loaded. The shoe 159 extends close to the forward end of the tube and hence remains depressed until the missile has entirely cleared the guide tube.

The guide tube housing 133 may be provided on one side with a latch pin receiving opening 162 to receive a horizontal stowage pin 163 which when in place locks the guide tube in the horizontal stowed position illustrated in Fig. 1. Actuating mechanism for the horizontal stowage pin 163 is illustrated in Figs. 11 and 12 where pin 163 is shown connected to one arm of a bell crank 164, the other arm of which is connected to rod 165 operable by hand crank 166. In order to secure the guide tube in its vertical loading position there is provided on the undersurface of the guide tube an apertured lug 167 (Fig. 14) having an inclined lower edge 168 and elongated opening 169. This lug cooperates with an axially slidable (spring biased) lock pin 170 (Fig. 12) mounted upon one cheek of the carriage and having a rounded end whereby it may be cammed back out of the way by the inclined face 168 to then snap into opening 169 and retain the guide tube in its vertical "load" position and prevent unintended movement from that position during loading. The pin 170 is controlled in its movement by a solenoid which, when energized, may act through a suitable operating means, not shown, to retract the pin against spring compression and permit the guide tube to be moved out of its vertical position. As shown in Fig. 14 the after portion of the guide tube has secured to its undersurface a pad 171 which, when the guide tube reaches vertical strikes a stop device such, for example, as pin 172 of a hydraulic buffer (Fig. 12) to cushion the movement of the guide tube to its vertical position. A similar pad 173 may be disposed to abut stop 174 (Fig. 12) to provide a positive stop which is engaged after the buffering action has taken place. This assures positive vertical alignment of the guide tube with the launcher hoist.

The undersurface of the forward portion of the guide tube (Fig. 13) may be similarly provided with a pad 175

which abuts a buffer pin 176 (Fig. 11) when the guide tube is depressed to approximately minus 10°.

To flame seal the upper end of the launcher hoist when the guide tube is not vertical there is provided a hatch 177 (Figs. 12 and 12A) which may be mounted for pivotal movement about a vertical pin at 178 and bears an upstanding cam pin 179 which, when the hatch is closed, is disposed in the path of a curved groove 180 formed in a door operating cam block 181 mounted on the rear of the guide tube. The hatch 177 is normally held in flame seal position by means of a pivotally mounted latch arm 177a having a hooked end portion which is urged against cam pin 179 by a spring 182 so as to force the edge of the hatch against a stop plate 179a. As the guide tube pivots towards vertical position the face of cam block 181 engages an upstanding striker pin 181a on the latch arm thereby pivoting the latch arm rearwardly and freeing the hatch from the tension of spring 182. It will be apparent that continued movement of the guide tube towards vertical causes the pin 179 to enter the groove 180 and be cammed to one side by the curvature of slot 180 causing the hatch 177 to swing out of the way of the rear end of the guide tube. This uncovers the top of the launcher hoist simultaneously with movement of the guide tube into the vertical position so that missiles issuing from the hoist enter directly into the rear of the guide tube. When the guide tube starts its return movement to depressed position the camming action of pin 179 in groove 180 causes the hatch to pivot to its closed flame sealing position where it is held in place by the force of spring 182 urging it against the stop plate 179a.

For cold weather operation suitable heating elements may be mounted along the length of the guide tube and at other locations adjacent important operating parts of the launcher mount so that they may be retained at operating temperature in spite of low ambient temperatures.

In order to prevent firing of the launcher when it is aimed at the ship's own superstructure and also in order to prevent firing when the launcher elevation exceeds 60° there may be provided on the mount a firing interlock cam of any suitable type which may be located within housing 195 and which cam may be adjustable in the conventional manner to control the limits of train and elevation during which firing of the launcher may occur.

The launcher hoist

The launcher hoist 102 raises missiles from a ready service magazine 101 into the after end of the guide tube 103 when the latter is disposed in the vertical load position. The upper end of this hoist is shown in Fig. 17 as a hollow tube 240 concentric with the axis of rotation of the launcher mount. As indicated in Figs. 1 and 2 the launcher hoist tube 240 has an adjacent hoist rammer chain guide housing 241 at one side thereof. Within this housing is located a rammer chain 124 and the housing 241 serves to guide rollers 243 on this chain so that a rammer spade 244 may be raised and lowered to lift missiles through the hoist tube and into the launcher tube.

As shown in Fig. 18, the chain 124 is of the conventional rammer type which will flex only in one direction and may be driven by a sprocket type driving member 245 mounted on shaft 246 and engaging with a helical gear 247. This helical gear mates with a larger helical gear 248 mounted upon shaft 249 and connected to a crank arm member 250. Any suitable means such as a rack or, if desired, a one-way chain 251 having rollers 252 is secured at its upper end to a piston shaft 253 bearing a piston 254 slidable within a hydraulic cylinder 255. Movement of the piston shaft 253 downwardly is transmitted through a rack or chain 251 to the crank arm member 250 to rotate the gears and raise the rammer chain and its lifter 122 to hoist a

missile upwardly through the launcher hoist tube. In the embodiment illustrated the gearing is preferably such as to provide a 1 to 5 ratio between the downward movement of the piston 254 and the upward movement of the lifter 122. Suitable hoist raising and lowering interlock switches may be mounted in a control group 256.

The ready service magazine

The ready service magazine is shown in Figs. 3, 10, 19, 20, 21, and 22 and comprises a circular drum shaped framework of peripherally disposed channel like guide members 120, each spaced from the other a sufficient distance to receive a missile therebetween, the entire framework being mounted for rotation about support bearings 116 shown in detail in Fig. 19. As there illustrated, the ready service magazine drum includes a radially extending flange member 257 spaced between upper and lower roller bearings 258 and 259, respectively. A similar roller bearing arrangement 260 is provided to receive radial thrust. In order to rotate the ready service magazine 101 there may be provided a pinion 261 mounted upon a shaft 262 driven by power drive means located within the magazine. This pinion drives the magazine drum through engagement with the teeth of an internal ring gear 263.

As shown in Fig. 20, there may be provided adjacent the ring gear 263 a flange having a plurality of stop receiving notches 264 which may be engaged by a suitably actuated stop member 265 comprising a ready service drum latch mechanism. Engagement of this stop member 265 in a notch latches the drum with one stall in registry with the launcher hoist and another stall in registry with the stowage hoist.

Figs. 21 and 22 are enlarged views of the bottom portion of a ready service drum stall showing the details of a missile support latch 266 and a stall loaded indicator cam 267. It will be noted that the missile support latch 266 pivots about pin 268 and is normally held in missile engaging position by a suitable spring 269. With this arrangement, as a missile is fed upwardly from the stowage hoist hereinafter to be described, the stall is loaded from below and the forward end of the missile forces the missile support latch back until the shroud of the missile clears the latch, whereupon spring 269 moves the latch behind the missile and into missile supporting position. During the process of loading missiles from the ready service magazine drum into the stowage hoist it is necessary to detract the missile support latch so as to permit the missile to lower and for this purpose the after lower edge of the missile support latch member 266 is provided with an extension 271 which may be engaged by the overhanging lip 273 of a tripping head 272 mounted upon stem 274 extending downwardly and actuated by any means found suitable for the purpose to retract the missile support latch during missile stowage operation. Suitable grounding means well-known in the art may be employed to contact the body of the missile and maintain it at ground potential.

Switch BK is connected with missile support latch 266 for actuation from its normally closed position to an open position when the missile support latch is rotated about pin 268, and may be connected to a suitable electrical system for either producing a signal or an interlock action or both, as may be desired.

The stall loaded indicator may comprise a cam member 267 which has inclined upper and lower faces presented to the stall so that it will be cammed out of the stall when a missile is moved into place. This cam may be hinged at one side as by bolt 275 and is normally urged into the stall by a suitable compression spring 276.

There are provided one missile support latch and one stall loaded indicator for each stall, the stall loaded indicators actuate switches BJ-1 and 2 and BJ-3 the operat-

ing arms of which ride upon a ramp 279 which has inclined surfaces at each end.

The stowage hoist

5. The above-deck mount, launcher hoist and ready service magazine operate together during automatic firing operations to load and fire missiles as long as the supply in the ready service magazine holds out. However, when said supply is exhausted it is necessary to replenish the ready service magazine from the ship's store of missiles and this is accomplished through a stowage hoist illustrated in Figs. 23 to 28, inclusive, and Fig. 30. This stowage hoist may extend one or more decks below the ready service magazine and is disposed in alignment with one of the peripheral stalls of the drum when the latter is latched in place and sufficiently spaced from the launcher hoist to prevent interference therewith. As a practical matter it has been found that it may be located at any position three or more stalls distant from the launcher hoist. By this arrangement missiles may be stowed in a well protected compartment on suitable racks and may be moved to the stowage hoist by conventional conveyor means.

As shown in Fig. 23, the stowage hoist comprises a tubular upper trunk 285 and a missile receiving lower trunk 286 which has a tray portion 287 hinged at 288 to permit the tray to be lowered down to a substantially horizontal position to receive a missile. In use, a missile is placed upon tray 287 by suitable conveyor means whereupon suitable controls located on a control panel may be actuated by the stowage hoist operator to cause the tray to be raised through the medium of an actuator of any desired type such, for example, as hydraulic raising cylinder 290 which may be connected to operate through one-way chain 291 upon a sprocket sector 292. This pivots the tray about a point 288 and raises the missile to a vertical position within the lower trunk portion 286 of the hoist. When the missile is in such vertical position its base rests upon a semicircular platform 293, one edge of which is cut away to accommodate a stowage hoist lifter 294. With the tray closed and the missile in position and with suitable interlocks and control circuits properly actuated the hoist lifter 294 may be raised by the operation of a motor 295 acting through a suitable transmission 296 upon a one-way chain 297 to raise the missiles into an empty stall of the ready service ring immediately over the stowage hoist upper outlet.

In Fig. 24 is illustrated in detail a missile clamping arrangement whereby opposed arms 298 and 299 may be linked together to retain the missile on the tray against unintended movement while it is traversing the distance from its horizontal load position to a vertical hoist position. As there shown, the arm 299 pivots about a pin 300 and has a downwardly projecting bifurcated extension 301, between the arms of which is pivoted one end of a pair of link arms 302, which in turn are linked pivotally with the ends of a second pair of link arms 303 and 303a which are journaled in bosses 304 depending from the undersurface of the tray 287. These link arms 302 and 303 form a toggle linkage arrangement which because of stops (302a) can break only in one direction. Upright arm 298 is provided with a similar toggle linkage. Projections 303b on each toggle are connected by a spring 305 which normally urges the arms 298 and 299 to approach to each other in missile grasping relationship. When the tray 287 is lowered the toggle linkage is broken by engagement of the knee of the toggle with spaced upright posts 306 positioned on the floor of the stowage room and in alignment with said knees. It will be apparent that with the tray at rest in its horizontal position the arms are separated and a missile may be loaded on the tray, however, as soon as the tray is lifted enough to free the knees from the upright posts 306, then spring 305 causes the arms 298 and 299 to grasp the missile. In order to control the operation of the stowage hoist and

to provide electrical interlocks to prevent improper sequence of operation there are provided a number of electrical switches and actuating mechanisms therefor as follows.

In Fig. 25 is shown stowage hoist lifter upper limit switches CC1, 2 which are mounted near the base of the stowage hoist trunk (Fig. 23) and may be actuated by a cam 308 mounted upon the stowage hoist rammer chain 297 when the lifter reaches the upper extent of its travel. To accomplish this a roller 309 is mounted on a block 310 for sliding movement and the block is normally held inwardly by a spring and has a stem adapted upon outward movement of the block to engage the tip 311 of an actuating arm 312 pivoted at 313 and having a portion 314 which engages the actuating roller of switches CC1, 2. Engagement of cam 308 with roller 309 actuates switches CC1, 2 to reverse the direction of movement of the hoist lifter.

In Fig. 26 is shown in enlarged detail the stowage hoist lower chain limit switches CA1, 2, 3 and CA4 which are arranged for simultaneous actuation by a chain mounted cam 317 as follows: when the cam 317 in its upward movement reaches the position shown it engages a roller 318 mounted upon the end of a slidable block 319 which is normally spring biased inwardly but has a stem 320 which upon outward movement engages a crosspiece 321 to operate levers 322 and 323 pivoted at 324 and 325. Outward movement of the block 319 opens the contacts of switch CA4 and closes the contacts of switch CA1, 2, 3.

Fig. 27 shows a switch operating mechanism whereby tray latch switch CB1, 2, 3 and a tray lowering switch CF may be actuated when desired. Considering first the tray tray latch switch CB1, 2, 3, its operating crank arm 328 has a pin at the end which rides in a yoke 329, keyed to a shaft 330. Likewise secured to said shaft is a bell crank 331 at one end of which engages links 332 connected to a second bell crank 333 pivoted at 334 and having an elongated operating arm 335 which is positioned in the bifurcated end of a reach rod 336 and connected thereto by a pin 337 movable in elongated slots 338 in the bifurcated end. The tension spring 339 secured to the end of the operating arm normally urges that arm upwardly. In the position indicated in Fig. 27 a stop lug 340 of the bell crank 331 abuts the end of a stop arm 341 pivoted at 342 and having a downward extension terminating in a spring biased tip 343. Spring means 344 serves to retain the stop arm 341 normally in the position indicated in Fig. 27.

As the tray 287 is raised to move a missile into the lower hoist trunk the end 345 of the tray forming a part of the flame seal brushes against the dangling tip 343 of the stop arm 341 to rotate that arm about its pivot 342 and lift the end abutment thereof out of the path of the stop lug 340 on the bell crank 331, thus permitting the spring 339 acting through the linkage aforesaid to move the stop lug under the end of the arm 341 and hence through the yoke 329 actuates switch arm 328 to close contacts CB1, 2 and open contacts CB3 thereby to condition the control system so that the stowage hoist may operate to raise the missile up through the trunk and into an empty stall of the ready service magazine. When the T handle 346 is grasped and pulled, reach rod 336 moves downwardly and ramp 347 thereon bears against the operating arm of tray lowering switch CF to close that switch and condition the control circuit to initiate downward movement of the tray.

Fig. 28 shows the actuating means employed for operating a tray loaded switch CD1, 2, 3, 4 and a tray position indicator switch CL. The former is operated when a missile has been correctly positioned on the tray by downward movement of missile engaging foot treadle 359 which pivots upon shaft 351 and moves a clevis rod 352 which rotates lever 353 about a pivot shaft 354 against the tension of spring 355. All of these parts

are located on the undersurface of the tray and pivot shaft 354 has keyed for movement therewith an inwardly extending arm 356, the end of which is yoked and rides in a grooved collar 357 mounted upon an axially slideable sleeve 358 which floats about tray pivot shaft 288. The opposite end of the floating sleeve 358 has a flange 359 against which roller 360 on one arm of bell crank 361 bears. The other arm of the bell crank engages a clevis shaft 362 linked to a switch actuating arm 363 of the switch CD1, 2, 3, 4.

The tray position indicator switch CM has an arm 364 with a roller thereon which bears against cam surface 365, the contour of which conforms to the position of the tray and serves to close the switch CM when the tray is fully closed. Likewise, an interlock switch CL has a similar arm in engagement with the periphery of a cam 374 which serves to close switch CL when the tray is fully down.

It will be apparent that rockets or missiles must be loaded from above-deck down into the ship's stowage magazine and for this purpose the ready service magazine drum may be employed to carry missiles from the loading hatch 366 into alignment with the stowage hoist opening 369. Missiles are loaded into the ready service drum through hatch 366 (Fig. 30) through which they are lowered by means of a conventional crane 367 and motor operated hoist 368. Thereafter the drum may be rotated to position the missile immediately above the stowage hoist lifter 294 (Fig. 23) which may be raised empty and, at the top of its stroke, receive the missile to thereafter lower the same to the bottom of the stowage hoist, whereupon operation of the T handle reach rod 346 will cause the tray to lower to horizontal position with the missile thereon. As the tray reaches its horizontal position the arms 298 and 299 automatically release from the missile and it may be lifted by any suitable hoist means and conveyed to a rack for stowage.

It is during the missile stowage operation that the missile support latch 266 (Fig. 21) which supports the missile in the ready service drum stall is withdrawn by engagement of tripping head 272 therewith. This permits the missile to rest on the lifter 294 and be lowered thereby. The tripping head 272 may be actuated by any suitable means such as the lever 370 (Fig. 23) pivoted at 371 and moved by energization of solenoid SCE to raise armature 373.

Operation

In the above description has been set forth the structures and functions of the guide tube and its mount, the launcher hoist, the ready service magazine, and the stowage hoist and tray. The following discussion is concerned with the operation of the entire launcher equipment during loading of the stowage magazine, automatic fire, re-loading of the ready service magazine from the stowage magazine, and testing and casualty operations such as would be encountered by actual use of a launcher embodying the present invention. For this purpose, it will be assumed to start with that the launcher mount is in stowed condition and that both ready service and stowage magazines are empty.

As before-mentioned only a minimum number of personnel is necessary in order to carry out the above operations with the present missile launching equipment. These personnel are located at suitable control panels. As there shown a "mount operator," a "stowage hoist operator" and a "striking down controlman" are located below decks while above-deck missile handlers may assist during missile striking down operations. In addition stowage magazine personnel transport missiles from the tray to missile stowage racks in the main stowage compartments of the vessel and similarly transport the missiles to the stowage hoist tray when loading the ready service magazine with a supply of missiles to prepare the launcher for operation. It will be noted that with the present launcher equipment the missiles need never be lifted by hand and

therefore large and cumbersome missiles may conveniently and rapidly be handled and launched.

Striking down operations.—There will first be considered the operations necessary to lower missiles into the ready service magazine and thereafter lower missiles from the ready service magazine into the ship's stowage magazine by the use of the stowage hoist. This loading operation is commonly referred to as a "striking down" operation.

During this procedure the ready service drum serves as a conveyor to move the missiles from a position below a striking down hatch in the weather deck to a position above the stowage hoist by which latter they then may be lowered into the ship's missile stowage magazine area. In these striking down operations either of two procedures may be employed; a number of successive magazine stalls may each be loaded with a missile and then the several missiles may sequentially be moved into alignment with the stowage hoist for lowering into the ship's missile stowage compartments or, in the alternative, a single missile may be lowered into a stall and the ready service magazine then indexed so as to position that missile above the stowage hoist.

As shown in Fig. 30, a conventional crane 367 and a hoist 368 may be used to support a missile 118 over a striking down or loading hatch 366 through which the missile may be lowered into an empty stall of the ready service magazine drum. Suitable precautions are taken to prevent starting of the train and elevation motors during the striking down stowage operation. When the ready service drum is in condition to be loaded, a missile may be lowered from above through hatch 366 into an empty stall directly beneath the striking down hatch. When the shroud at the lower end of the missile rests on the missile support latch in the lower end of the stall, the crane cable is unhooked and the "striking down controlman" signals the "mount operator" who then indexes the ready service magazine one position and places the next empty stall directly beneath the striking down hatch. This procedure is repeated until the desired number of missiles are in the ready service magazine stalls. The number of missiles lowered into the ready service magazine will depend on the method of loading, as explained above. The "mount operator" may be notified when to rotate the ring by prearranged signals from the striking down station. The next step in the striking down operation involves lowering missiles from the ready service drum to the ship's stowage magazine. (As the hoist tray acts as a flame seal, a missile should never be in position above the magazine hoist unless the tray is raised and latched; consequently, an interlock circuit may be so arranged that the ready service magazine cannot be rotated until the latter condition exists.) The "stowage hoist operator" is signalled so that he may be informed that power is on and that striking down operations are in progress.

Thereafter, the striking down controlman causes the stowage hoist to be raised. At the top of its stroke, the hoist lifts the missile above the missile support latch at the bottom of the magazine stall and stops. Then the "striking down operator" causes the missile support latch to be withdrawn. Withdrawal of this latch closes switch BL in an interlock circuit and the stowage hoist automatically starts downwardly, lowering the missile to the vertically-positioned tray at the bottom of the hoist. The start of the up and down travels of the stowage hoist are indicated to the "mount operator" by appropriate signals.

When the stowage hoist with a missile reaches the bottom of its stroke, the "stowage hoist operator" is so informed by a suitable signal and he then pulls on the T handle 346 to retract the tray latch and the tray will then lower the missile to a horizontal position. The exposed missile may thereafter be removed from the tray by stowage room personnel and transported to suitable stowage racks.

After the missile has been removed from the tray, the "stowage hoist operator" causes the tray to pivot to the vertical position where it automatically latches whereupon the "mount operator" is signalled that the tray is now latched. Thereafter, the "mount operator" causes the ready service magazine to be rotated one position, and so place the next loaded stall over the magazine hoist. The missile lowering operation is then repeated. Indexing of the ready service magazine also places an empty stall under the striking down hatch, and if desired another missile may be lowered into the empty stall by the whip hoist. Through the use of signals from the "striking down controlman" to the "mount operator" the action of personnel at both of these stations can be coordinated to load missiles into the stowage magazine from topside as a continuous operation.

Loading ready service magazine from below.—The ready service magazine may be loaded from below when it is desired to prepare the launcher for a state of readiness for action. In order to accomplish this the "mount operator" first starts the hoist motor and conditions the control circuits. He then signals the "stowage hoist operator" who then pulls the T handle 346 and the tray lowers to a horizontal position.

When a missile has been correctly positioned on the tray, the "stowage hoist operator" causes the tray and missile to be raised to the vertical position whereupon the stowage hoist automatically raises the missile into the empty ready service magazine stall directly above the hoist, raising the missile high enough to clear the missile support latch which snaps back to its normally extended position under the missile shroud. The stowage hoist then reverses direction and starts downwardly, but the missile is retained in the ready service magazine stall by the missile support latch. When the stowage hoist reaches the bottom of its stroke, one loading cycle will have been completed and the ready service magazine can be indexed by the "mount operator" to permit the next stall to be loaded in similar position. This is continued until the ready service magazine is filled.

Launcher hoist test.—It is desirable from time to time to raise and lower the launcher hoist without a missile so as to test the operation of the hoist and be sure that it is in proper operating condition. This may be done only when the guide tube is in vertical position and the hoist motor has been started as described above. When so conditioned the "mount operator" causes the empty hoist to rise at normal speed to the upper limit of its travel and return automatically at normal speed to its lower position.

Automatic firing run operation.—When the ready service magazine is loaded and the entire launcher is prepared for operation, the "mount operator" may set up his control panel, not shown, for automatic firing operation by the proper actuation of certain components, not shown.

Immediately the guide tube, if horizontal, will pivot to vertical "load" position and a missile will be hoisted from the ready service magazine up into the guide tube which will then move downwardly beyond 60° elevation, whereafter it operates in response to signals received from the ship's fire director system and will follow the ship's director until the firing circuit is closed to launch the missile from the guide tube, whereafter the tube will pivot upwardly to receive another missile. This loading and firing cycle will continue until all of the missiles in the ready service magazine have been fired in rapid succession without any further action on the part of launcher personnel, or until the firing circuit is left open. When the ready service magazine becomes empty it will continue to rotate intermittently until stopped by the "mount operator." Such automatic operation is schematically indicated in Figs. 4 to 9, inclusive, and the time cycle of operation of Fig. 29.

In the event the automatic "run" operation is stopped with an unfired missile in the guide tube this missile may

be returned to the ready service magazine as follows: the "mount operator" turns all switches to "off," the train and elevation drives at the mount are shifted from automatic to manual operation, the guide tube is elevated manually to its vertical position and the mount is trained manually to a position where the hoist lifter 122 will not strike the missile support latches 135. The ready service drum is momentarily operated to rotate the drum one stall counterclockwise, the hoist lifter 122 is raised so as to engage the bottom of the missile shroud to raise the missile off of the missile support latches whereupon the missile support latches 135 may be manually retracted by lever 142 (Fig. 14). Then the hoist lifter with the missile is caused to descend and return the missile to the empty ready service magazine stall.

Obviously many modifications and variations of the present invention are possible in the light of the above teachings. It is therefore to be understood that within the scope of the appended claims the invention may be practiced otherwise than as specifically described.

What is claimed is:

1. A device for loading and launching a plurality of missiles in rapid succession comprising; a guide for directing the initial flight of the missiles and supported for oscillating movement from an inclined firing position to a vertical loading position, a ready service magazine for carrying a plurality of missiles and sequentially presenting the carried missiles to a position below and in longitudinal alignment with said guide when the latter is in loading position, and means for sequentially loading missiles from the ready service magazine through a straight, vertical path into the guide when the guide is in vertical loading position.

2. A device for loading and launching a plurality of missiles in rapid succession comprising; a guide for directing the initial flight of the missiles and movable from a vertical loading position to an inclined firing position, a rotatable ready service magazine for carrying a supply of missiles and sequentially presenting the carried missiles to a position below and in longitudinal alignment with said guide when the latter is in loading position, and hoist means operable in timed relationship with the rotation of the ready service magazine for sequentially conveying missiles from the ready service magazine through a straight path to the guide when the guide is in vertical loading position.

3. A device for loading and launching a plurality of missiles in rapid succession comprising; a guide for directing the initial flight of the missiles and movable from a vertical loading position to an inclined firing position, a rotatable ready service magazine supporting a plurality of missiles for successive movement into vertical alignment with the guide when it is in vertical loading position, and hoist means operable in timed relationship with the rotation of the ready service magazine for sequentially conveying missiles from the ready service magazine into the guide when the guide is in vertical loading position.

4. An automatic missile launcher and loading mechanism comprising an above-deck mount, a launcher guide pivotally supported on the mount and movable from an inclined firing position to a vertical loading position, means for pivoting the guide between said positions during automatic operation, a below-deck missile magazine supported independently of the mount and having a plurality of missile receiving stalls longitudinally alignable in sequence with said guide when the latter is in loading position, and a stationary launcher hoist having a missile lifter movable through a vertical straight-line path adjacent the missile for linearly conveying missiles from the sequentially aligned stalls into the guide when the latter is in loading position.

5. A device for successively loading and launching a plurality of missiles comprising in combination; a guide for directing the initial flight of the missiles, a trainable

mount supporting the guide for movement from a loading position to a firing position; means for moving the mount in train, means for moving the guide from loading position to firing position, the guide when in loading position being disposed in coaxial alignment with the axis of train of the mount, a launcher hoist positioned to raise and lower missiles in a straight-line path along the axis of train, a ready service magazine below the mount and having stalls to support a plurality of missiles adjacent the launcher hoist, the magazine being movable to successively position missiles in coaxial alignment with the axis of train so that they may be raised by the launcher hoist and deposited in the guide when the latter is in its loading position, the stalls of said ready service magazine being reloadable from below, and a separate stowage hoist to reload missiles into the magazine stalls from below.

6. In an automatic missile loader and launcher the combination of; a trainable mount, a guide for directing the initial flight of a missile, and supported on the mount for oscillating movement from a vertical loading position to an inclined firing position, means for oscillating the guide between the positions, a hoist registering with the lower end of the guide and in longitudinal alignment with said guide when the latter is in vertical loading position, the guide and its mount being rotatable about the upper end of the hoist so that a missile may be hoisted into the guide during training movement of the mount.

7. In an automatic missile loader and launcher; a trainable mount, a missile guide supported on said mount and movable in train therewith, means for moving the guide in elevation from an inclined firing position to a vertical loading position at which time the axis of the guide aligns with the training axis of the mount, and hoist means in longitudinal alignment with the after end of the guide in loading position for loading missiles along a straight-line path into the after end of the guide when it is in loading position and during training movement of the mount.

8. In a loading and launcher mechanism for successively loading and firing a plurality of missiles; a vertical, straight-line missile hoist, a ready service magazine for automatically presenting missiles to the hoist in sequence, a rotatable launcher mount supporting a guide for movement from an inclined firing position to a vertical loading position in which the guide, the hoist, and the presented missile in said magazine are in substantial longitudinal alignment, the amount being located at the upper end of the hoist and rotatable thereabout, the axis of rotation of said mount substantially coinciding with the longitudinal axis of said hoist whereby a missile may be hoisted from the ready service magazine into the guide during rotation of the mount.

9. In an automatic loading and launcher mechanism the combination of; a guide for directing the initial flight of a missile, a guide being movable between a firing position and a loading position, the guide at its loading position being in alignment with the axis of train, a hoist including a missile engaging lifter movable along the axis of train for loading missiles into said guide, and a ready service magazine for successively delivering missiles into the path of the lifter.

10. In an automatic missile loading and launcher mechanism the combination of; a trainable mount, a guide carried by said mount for directing the initial flight of a missile and movable in elevation from an inclined firing position to a vertical loading position coaxial with the axis of train of the mount, a missile hoist for loading missiles into the after end of the guide, a hoist lifter member reciprocably carried by said hoist and movable in a straight-line path parallel with the axis of train of the mount, a ready service magazine adjacent the missile hoist and supporting a plurality of missiles therein, means for operating the magazine to successively present missiles to the hoist, each of said successively presented

missiles being positioned with the longitudinal axis thereof in alignment with the longitudinal axis of said guide in loading position, and means on said magazine for enabling said hoist lifter member to engage each missile after the latter is presented to the hoist and to move the missile in a vertical straight-line path into the guide.

11. In a loading apparatus for automatic missile launchers wherein a missile guide tube pivots from depressed firing position to vertical loading position the combination of; a ready service magazine having a plurality of open ended missile receiving stalls successively movable into longitudinal alignment with the guide tube when in loading position, a launcher hoist for successively hoisting missiles from the aligned stalls along a straight-line path into the guide tube, a stowage area, and a stowage hoist in said stowage area for sequentially moving successive missiles in the stowage area from a horizontal position to a vertical position in longitudinal alignment

5

with successive ones of said missile receiving stalls in said ready service magazine and feeding said missiles in the stowage area along a vertical, straight-line path into the successively aligned ready service magazine stalls.
